CHRISTIAN CORNELIS VAN DER VALK, OF VOORBURG, NEAR THE HAGUE,
NETHERLANDS.

GOLD-WASHING MACHINE.

SPECIFICATION forming part of Letters Patent No. 760,664, dated May 24, 1904.

Application filed August 19, 1903. Serial No. 170,027. (No model.)

To all whom it may concern:

Be it known that I, CHRISTIAN CORNELIS VAN DER VALK, a subject of the Queen of the Netherlands, and a resident of Voorburg, near The Hague, Netherlands, have invented certain new and useful Improvements in Gold-Washing Machines, of which the following is a specification, reference being had to the accompanying drawings.

10 The subject of my invention is a machine for extracting as completely as is possible the gold or other precious metal contained in earth or sand which has been dredged or dug out, in contradistinction to rock or ore. By means 15 of this machine gold can be obtained in a much more efficient manner than is possible with the apparatus ordinarily employed—such as Bate's apparatus—or hand-washers, which are difficult to handle, so that but few workmen possess 20 the necessary dexterity in order to obtain the whole of the metal contained in the earth.

The invention is illustrated in the accompanying drawings, in which—

25 Figure 1 shows a vertical section of the machine, and Fig. 2 a plan of that portion of the machine which lies between the lines A B and C D of Fig. 1. Fig. 3 is a plan of that portion which lies below the line C D of Fig. 1.

30 The new machine consists of sheet-metal hopper 1, fitting into the correspondingly-shaped support 3. In the base of the hopper is a central aperture coinciding with the spherical recess 2 in the support 3. The latter is 35 secured to the top of a rod 15 and is therefore compelled to partake of all the movements of the said rod, as will be hereinafter more fully described.

30 The top end of the rod 15 has its bearing in the semispherical block 5, in which it can turn and at the same time reciprocate in vertical direction. The block 5 rests in a slide 4, in which it can be rocked. The slide 4 is guided by two uprights 6 and by means of the lever system 7 8 9 10 can be adjusted vertically and secured in the desired position by the aid of the notched arc 11. The bottom end of the rod 15 is provided with a fork 17, in which a small roller running on the toothed disk 20,

is mounted. The disk 20 is rigidly secured to 50 the frame 14 of the machine by means of the connecting-pieces 31, as clearly shown in Fig. 3. If, therefore, the fork 17, with its roller, is caused to travel in a circular path over the disk 20, the roller, following the contour of 55 the teeth on the latter, will impart to the rod 15, and therefore also to the hopper 1, a regular up-and-down motion.

The fork 17, with its roller, is caused to travel over the disk 20 in the manner indicated 60 by means of the following device: In the center of the disk 20 is a pin 22, which by means of the toothed gear-wheels 27 and 28 and the spindle 29, rotated by hand or power, is given a constant rotary motion. The wheels 27 and 65 28 are keyed to their axes 22 and 29, respectively, in the ordinary manner. On the top of the pin 22 is keyed a sleeve 23, having guide-pins 24. On the latter there slides a forked block 25, in the outer end of which is 70 mounted a small roller which travels over the surface of a toothed ring 21. Between the block 25 and sleeve 23 is a spiral spring 26, located between the pins 24 and always tending 75 to force the block 25 and its roller outward against the teeth of the ring 21. In the block 25 is a square hole forming a bearing for the fork 17, which is at this part of square section and can slide in the hole.

The ring 21, like the disk 20, is rigidly secured to the machine-framing by the pieces 80 31. If, therefore, the spindle 29 is turned so as to cause the sleeve 23, and thus the block 25, to rotate in the direction of the arrow in Fig. 3, the block 25, with its roller, the fork 85 17, and rod 15 will follow a sinuous path presented by the teeth of the ring 21. In this manner the hopper 1, in addition to its up-and-down motion, as already described, will receive a lateral shaking or oscillatory motion. 90 Thus if the hopper 1 is charged with the metalliferous mass (earth, sand) and the machine set in operation the specifically heavier portions of the mass—*i. e.*, the metallic particles—will, by reason of the just-described movements of the hopper—that is, the shocks acting upon the latter—have the tendency to advance toward the center of the hopper. In 95

order to prevent the same side of the hopper always being lowermost, such as would be the case if the fork 17 were rigidly connected to the rod 15, fork and rod are joined by means of a sleeve 16. The latter is rigidly secured to the rod 15, but allows the fork 17 to turn in it by means of an annular groove in the fork end and a pin in well-known manner.

Through the sleeve 16 there passes loosely a rod 18, connected to the machine-framing 14 by a universal (Cardan's) joint 19, so that it is capable of movement in all directions. By this means the rod 15, while the fork 17 and its roller are traveling in a circular path over the disk 20, will always present one and the same point of its circumference toward the same side, or, in other words, is prevented from rotating during its circular swinging motion inside the framing 14. From this it follows that all points of the circumference of the hopper 1 must alternately and in order assume the highest and lowest positions, Fig. 1, so that the entire contents of the hopper must gradually move over the center of the latter.

By altering the height of the slide 4 it is obvious that the extent of the oscillations of the hopper can be changed as desired.

Suitably secured to the wall of the hopper 1 is a cover 32, by opening which access can be had laterally to the interior.

The operation of the machine is as follows: The hollow space 2 is partly filled with mercury and the hopper 1 then charged with the metalliferous earth to be treated, which must first have been freed of all stones and then stirred up with water to form a muddy mass. The spindle 29 must now be rotated and the whole machine thus set in operation. In consequence of the combined shocks in vertical and horizontal directions, which, owing to the arrangements already described, are exercised continuously upon the hopper, the specifically heavier materials of the mud contained in the latter will commence to shift toward the center of the hopper and finally will all collect at the center—that is, above the recess 2. So far as these specifically heavier parts are gold or another metal soluble in mercury they will be amalgamated by the mercury contained in the recess 2 and can subsequently be separated from such mercurial mass by well-known process. In this manner even the very finest particles of metal—*e. g.*, gold-dust—distributed in the earth can be extracted. To obtain all the particles of precious metal contained in a hopper charge, it is sufficient to work the machine only for a few minutes. This being done, the machine is stopped and the hopper brought into the dotted-line position in Fig. 1 by means of the handle 10. The cover 32 must next be opened and the now completely-exhausted muddy mass removed from the hopper. The opening must then be closed again by the cover 32, when the hopper can be re-

charged with sand or earth mixed up to muddy consistency and the operation repeated. In order to separate the metal contained in the mercury in the recess 2, it is well to first press the mercury through linen to remove any floating particles of earth. The residue, with the mercury, may then be treated in the usual manner—for example, by volatilization—in order to separate the amalgamated metal.

The new machine operates so thoroughly that earth which has been already treated in the ordinary manner by means of machines of well-known construction may be treated again in the new machine, the further yield of precious metal rendering this lucrative.

Having thus described my invention, what I claim is—

1. A gold-washing machine comprising a receptacle the bottom of which runs downwardly toward the center, a non-rotating support for said receptacle, said support being provided with a recess, and said receptacle having an opening communicating with said recess and means for simultaneously giving said receptacle a constantly-changing inclination and an up-and-down motion, whereby the specifically heavier bodies contained in the charge in the receptacle are caused to advance toward said recess, substantially as described.

2. A gold-washing machine, comprising a receptacle 1, 3 the bottom of which runs downwardly toward the center, where a recess 2 for mercury is located, a rod 15 carrying said receptacle, means for preventing said rod from turning, a semispherical top bearing for said rod, a roller at the bottom of the latter, a stationary toothed disk 20, and means for rotating the roller over the teeth of the same, whereby the receptacle receives simultaneously a revolving and a regular up-and-down motion, substantially as described.

3. A gold-washing machine, comprising a receptacle 1, 3 the bottom of which runs downwardly toward the center, where a recess 2 for mercury is located, a rod 15 carrying said receptacle, a semispherical top bearing for said rod, a vertically-reciprocating slide in which said bearing is contained, means for adjusting and fixing said slide, a roller at the bottom of the rod, a stationary toothed disk 20, and means for rotating the roller over the teeth of the same, all substantially as and for the purposes described.

4. A gold-washing machine, comprising a receptacle 1, 3 the bottom of which runs downwardly toward the center, where a recess 2 for mercury is located, a rod 15 carrying said receptacle, a semispherical top bearing for said rod, a roller at the bottom of the latter, a stationary toothed disk 20 over which the said roller runs, a rotary spring-controlled lower bearing 25 for the roller-rod, a stationary toothed ring, located concentrically with the toothed disk, over the teeth of which ring the bearing 25 travels, and means for rotating the

said bearing with its rod, all substantially as and for the purposes described.

5. A gold-washing machine, comprising a receptacle 1, 3 the bottom of which runs downwardly toward the center, where a recess 2 for mercury is located, a rod the lower portion 17 of which turns in the upper portion 15 which carries the receptacle a semispherical bearing for the top of said rod 15, 17, a roller at the bottom of the latter, a stationary toothed disk 20 over which said roller runs, a rotary spring-controlled bearing 25 for the lower portion 17 of said rod, a stationary toothed ring 21 located concentrically with the said disk, over

the teeth of which ring the bearing 25 travels, an arm 18 passing crosswise loosely through the upper portion 15 of said rod and secured to the framing by a universal joint, and means for rotating the said bearing 25 with its rod, all substantially as and for the purposes described.

In witness whereof I have hereunto signed my name, this 22d day of July, 1903, in the presence of two subscribing witnesses.

CHRISTIAN CORNELIS VAN DER VALK.
